UNITED STATES PATENT OFFICE.

FRANK E. LIVERANCE, JR., OF GRANDVILLE, MICHIGAN.

HOOD LATCH.

Application filed March 28, 1927. Serial No. 179,085.

This invention relates to a hood latch designed for securing the hood doors in a motor vehicle in closed position, the same being readily released when the hood door is 5 to be lifted in order to gain access to the engine housed under the hood.

It is a primary object and purpose of the present invention to construct a latch very economically and provide it with an engaging handle which may be of a necessary width that it will not cut into or otherwise hurt the fingers of the one operating the latch, and to further provide a novel form of side engagement with the hood in order that 10 its lower edges may be held snugly against an abutment with which it engages and so as not to vibrate and rattle. It is purposed to make the latch almost entirely of sheet metal, the parts of which are readily formed 15 so that quantity production at low cost is secured.

For an understanding of the invention, reference may be had to the following description taken in connection with the 20 accompanying drawings, in which,

Fig. 1 is a side elevation of the latch showing the same applied to a hood door of a motor vehicle, said door and the abutment against which it engages being in vertical 25 section.

Fig. 2 is a vertical section on a plane perpendicular to the side of the hood door and centrally of the latch.

Fig. 3 is a perspective view of the latch.

Fig. 4 is a horizontal section on the plane of line 4—4 of Fig. 1, looking in a downward direction.

Fig. 5 is a somewhat enlarged perspective view of one-half of the latch housing.

Fig. 6 is a fragmentary side elevation and section illustrating a different form of side clamping construction than that shown in Fig. 2.

Fig. 7 is an elevation similar to Fig. 1 showing a modified form of latch construction.

Fig. 8 is a vertical section taken centrally through the latch on a plane parallel to the hood door, the door being shown fragmentarily in side elevation.

Fig. 9 is a horizontal section substantially on the plane of line 9—9 of Fig. 7 looking downward.

Fig. 10 is an enlarged under plan view of

one of the elements of construction used in 55 the latch shown in Figs. 7 and 8.

Fig. 11 is a perspective view of the base attaching plate used to connect the latch with the vehicle, and

Fig. 12 is a perspective view of the handle 60 of the latch.

Like reference characters refer to like parts in the different figures of the drawings.

In the construction of the latch, a housing is provided which consists of two parts 65 which are duplicates, each comprising a semi-cylindrical or half-round section 1, at one end having a narrow tongue 2 extending therefrom, and at the outer end terminating in a flat section 3 with interned 70 flanges 4 the free edges of the flanges and the edges of the half-round section 1 being in alignment. The flat section 3 with its interned flanges 4 is of substantially channel form. An opening 5 is made through the 75 web portion 3 thereof.

Each of these parts of the housing is formed of sheet metal stamped into shape. The handle for the latch comprises a separate member also of sheet metal, having a 80 lower section 6 the width of which is such that it fits between the flanges 4 of the two members of the housing when the same are placed together with their edges in contact. The handle is widened above the part 6 as 85 indicated at 7, curved to one side and upwardly and then back, as indicated at 8, terminating in an outwardly extending handle portion 9, it being evident that the hand of the operator may be placed underneath the curved section 8 and the portion 9 and a secure grasp thereon obtained. From the curved section 8 a hook 10 is struck, being curved away from the part 8 as shown. At the lower end of the handle member, that 90 is, at the lower end of the attaching section 6, the metal is slit substantially midway between its side edges and the parts at each side of the slit bent outwardly and downwardly at an angle away from each other 95 making the tongues 11.

With two of the semi-cylindrical housing members described and as shown at Fig. 5 placed together to form a substantially tubular housing, the attaching section 6 of the handle may be located between the webs 3 and with the flanges 4 extending toward and in contact with each other, and a rivet 100 105

12 passed through the openings 5 and through a like opening 5^a in the handle member to securely connect the parts together. The tongues 11 fit against the upper ends of the semi-cylindrical sections 1 and prevent any tendency of the handle to turn about rivet 12.

The housing member with the handle attached as described is open at the bottom. 10 Into the lower end of the housing the spring assembly is to be inserted and then secured in place. The spring assembly unit includes a lower attaching plate which secures the latch to the vehicle. This plate 13 at one 15 side is formed with an upwardly extending cup 14 slotted at one side, at 15, through which a rod 16 may be passed upwardly until a head 17 at the lower end of the rod bears against the under side of the cup 14. 20 On this rod a closing cap for the lower end of the housing is then placed. The cap has a circular base 18 with a continuous annular upwardly extending flange 19 around its edges and is of such size that the lower end 25 of the housing made by fastening together the two semi-cylindrical sections 1 fits within the flange and the lower ends of the housing come against the upper sides of the base 18. Base 18 of course has the proper openings punched therethrough for the passage 30 of the tongues 2; and it also has a central opening for the free passage of the rod 16. After the spring has been placed over the rod and against the cap, a shallow thin sheet 35 metal cup or washer 21 with a central opening for passage of the rod is placed over the rod against the upper end of the spring. The rod is then upset or flattened, as indicated at 22, so as to prevent the washer 21 40 moving upward beyond the upset portion of the rod. This spring assembly is inserted into the lower end of the housing, the lower cap moved until the tongues 2 extend through the base 18 of said cap, and then the 45 tongues are bent inwardly toward each other against the bottom 18 of the cap completing the assembly.

The latch is capable of use without further additions thereto but in Figs. 1 to 4 inclusive 50 I have shown a side engaging clamp or pressure member to engage against the outer side of a hood door and hold it against vibration or rattling when the latch is in service. A length of sheet metal is bent into curved 55 form, as at 23, so as to snugly fit around the housing of the latch and terminates in two spaced apart ears 24 which extend to one side of the housing. A cylindrical pressure member 25 of rubber has a metal sleeve 26 60 through it and this pressure member is located between the ears 24. A pin 27 shouldered at its ends having been passed through the sleeve 26 its ends extend through openings in the ears 24 and are headed or riveted over at the outer sides of the ears. 65

The part 23 may bear directly against the upper edge of the lower cap flange 19. The riveting of the ends of the pin 27 draws the ears 24 toward each other and clamps the part 23 tightly against the tubular hous- 70 ing.

The latch is attached in the usual manner by securing its base 13 to a frame member of the vehicle over which is usually a cover 28 of sheet metal the inner edge of which is 75 turned upwardly at right angles to make an abutment 29 against which the lower edge portion of the hood door 20 bear when the door is in closed position. A keeper 31 is permanently secured to the outer side of the 80 hood door 30 with which the hook 10 may be engaged on grasping the handle and pulling upwardly thereon so as to compress spring 20. After the hook is engaged with the keeper 31 the spring exerts a force on 85 the hook which is transmitted to the hood door 30 serving to hold it in lower position. At the same time the hook 10 is being engaged with the keeper 31, the pressure member 25 is brought against the outer side of 90 the hood door and as the hook is lowered into engagement with the keeper 31 the pressure member bears against the door and rolls about the axis of the pin 27. Accordingly 95 the door is pressed snugly against the abutment 29 and held against any vibration which would cause undesired noise.

In Figs. 7 to 12 inclusive, a different form of the invention is shown. The housing members 1^a, instead of being of semi-cylindrical form, are widened in one direction so that when two of them are placed together the cross section of the housing is of oval shape as shown in Fig. 9. This makes the distance between the flanges 4 greater 100 than in the structure shown in Figs. 1 to 5, and the handle need not be widened above the upper end of the housing as in the first described structure. Otherwise the handle is the same and its attachment to the housing member is the same. The lower closing cap is also of oval instead of circular shape, the base 18^a being shaped in accordance with the lower end of the housing. 105

Instead of using a rod like 16, a U-shaped 110 member made of wire or of rod smaller in diameter is used, it having a lower cross connecting portion 32 connecting the two spaced apart sides 33 of said U-shaped member. These sides 33 are located one at each 115 side of the spring 21, said sides passing upwardly through two spaced apart openings in the base 18^a. A cross bar 34 of sheet metal having oppositely extending wings 35 is placed over the two sides 33, the wings having openings to pass the same, and the intermediate portion of the cross bar 34 is formed with a downwardly extending annular lip 36 pressed from the metal and fitting 120 into the upper end of the spring 20. The 125 130

bar is secured in place a short distance below the upper ends of the sides 33 by flattened or upsetting the sides, as indicated at 37, at least above the bar, though as shown 5 in Fig. 8 they may be flattened both above and below the bar.

The assembly of this spring unit is the same as in the first described structure, namely, placing the spring between the lower 10 cap and the bar 34 and then inserting the upper ends of the parts 33 and bar 34 and the spring into the housing and securing the lower cap in place by means of the tongues 2. The attaching base for mounting 15 the latch is modified. It comprises a base 38 with a curved section 38 extending from one edge of substantially semi-cylindrical form with the open side down. This part 39 passes between the sides 33 and over 20 the connecting portion 32 whereby the latch is securely held in place and has a pivotal movement toward and away from the hood door, the same as the latch shown in Figs. 1 and 2 is permitted such pivotal movement 25 by reason of the slot 15.

The side engaging clamp shown in Figs. 7, 8, and 9 is somewhat modified being made of a greater height so as to bring the clamp at a higher point where it engages the door 30. The curved section 23^a is of a shape to fit the oval shaped housing and the ears 24^a extending therefrom extend from the upper part of the housing and are formed at their free edges with a number of inturned 35 prongs 40 which embed themselves in the rubber block 41 placed between them. A securing rivet 42 passes through the ears and the rubber block as shown.

In Fig. 6 the side clamp shown in Figs. 40 1, 2, 3, and 4, instead of being mounted on the latch, is mounted on the door. A base 43 is placed against the door and its ends 44 bent inwardly at right angles to pass through slots in the door 30 and then 45 clinched inwardly against the inner side thereof. Bars 45 extend outwardly from each side of the base 43, between which the rotatably mounted rubber member 25 is mounted the same as it is mounted between 50 the ears 24 in Figs. 1 to 4 inclusive.

This construction of latch is practical and simple to manufacture. The housing members are duplicates and are made with the same dies. The handle may be widened so 55 as to give the necessary bearing surface and not injure the hands of the operator. The two assembly units of the structure are easily assembled and then may be placed together and connected by merely clinching the 60 tongues 2 against the base 18 (or 18^a) of the lower closing cap of the housing. The rolling contact either between the rubber roller 25 and the side of the hood door as shown in Figs. 1 and 2, or between the roller

and the side of the latch housing as shown 65 in Fig. 6 is a feature of novelty and merit, there being no necessity of frictionally moving the rubber against any surface while at the same time pressing the rubber against such surface. 70

The invention is defined in the appended claims and is to be considered comprehensive of all forms of structure coming within their scope. 75

I claim:

1. A hood latch housing comprising, two halves made of sheet metal and located against each other, a handle of sheet metal having a hook struck therefrom secured at and between the upper ends of said halves 80 of the housing, a cap attached to and closing the lower end of the housing, and securing the two halves of the housing together at their lower ends, a spring within the housing, and a member passing through said cap 85 and normally acted upon by said spring to telescope said member into the housing.

2. A housing for a hood latch comprising, two separate parts of identical form located with their edges against each other, a handle 90 of flat metal disposed between and at the upper ends of said parts, means passing through the handle and said parts to connect the same together at their upper ends and a closing cap attached to and closing the lower 95 end of the housing and securing the parts together at their lower ends.

3. A housing for hood latches comprising, two parts of identical construction made of sheet metal and having inwardly bent upper 100 ends, a handle of sheet metal having a part located between the upper ends of said members, and means passing through said upper ends of the members and the handle for securing the same together. 105

4. A housing member for hood latches comprising two halves of sheet metal located with their edge portions abutting and having upper ends bent inwardly toward each other, a handle of flat metal having a lower portion passing between the upper inwardly bent ends of said halves of the housing, said handle at its lower end within the housing being slit vertically, and the parts at each side of said slit bent in opposite directions 115 to diverge from each other and come against the inner sides of the housing, and securing means passing through the upper ends of said housing and said handle.

5. A hood latch housing comprising two 120 halves of sheet metal having half round form except at their upper ends and at said ends being bent inwardly toward each other and having shallow channel form, said halves of the housing being placed together with their 125 edges abutting, a handle of flat metal having a lower end portion located between the upper ends of the housing and housed within

the channel portions thereof, and means securing said handle and halves of the housing together.

6. A hood latch comprising a housing, a handle of flat metal secured to the upper end of the housing extending vertically upward therefrom and thence being curved so as to extend upwardly and outwardly in one direction at an angle to the lower end of the handle, a hook struck from said curved portion of the handle and extending away therefrom, a spring within the housing bearing against the lower end thereof, and a

member slidable through the lower end of the housing and acted upon by said spring to normally cause said member to move upwardly into said housing.

7. A handle for hood latches comprising, a single piece of flat metal comprising a vertical section and a handle portion curved upwardly and to one side away from said section and an integral tongue struck from the handle portion and extending away therefrom.

In testimony whereof I affix my signature.
FRANK E. LIVERANCE, JR.
